UNITED STATES PATENT OFFICE.

ALEKSANDER TONKIEWITZ, OF PHILADELPHIA, PENNSYLVANIA.

WASHBOILER.

1,060,298.

Specification of Letters Patent. Patented Apr. 29, 1913.

Application filed August 28, 1912. Serial No. 717,611.

To all whom it may concern:

Be it known that I, ALEKSANDER TONKIEWITZ, a subject of the Czar of Russia, residing at Philadelphia, in the county of Philadelphia and State of Pennsylvania, have invented certain new and useful Improvements in Washboilers, of which the following is a specification, reference being had therein to the accompanying drawing.

10 This invention relates to wash boilers, and the objects of my invention are, first, to provide a wash boiler that is in the form of a bucket; second, to furnish the boiler with a clothes supporting device that prevents the clothes from being burned by the bottom of the boiler; third, to furnish the boiler with a device that permits of clothes being easily and quickly drained and removed from the boiler; and fourth, to accomplish the above 20 results by a mechanical construction that is simple, durable, inexpensive to manufacture and highly efficient for the purposes for which it is intended.

With the above and other objects in view 25 the invention resides in the novel construction, combination and arrangement of parts to be hereinafter specifically described and then claimed.

Reference will now be had to the drawing, 30 wherein:

Figure 1 is a vertical sectional view of a wash boiler in accordance with this invention, Fig. 2 is a plan of the same, and Fig. 3 is an enlarged vertical sectional view of 35 the device used in connection with the boiler.

A boiler in accordance with this invention comprises a tapering shell 1 having a flat bottom 2 that is suitably connected to the lower edges of the shell, while the upper 40 edges of the shell have a wire reinforced edge 3. The shell 1 and the bottom plate 2 provide a receptacle similar to a bucket, and this receptacle constitutes the wash boiler.

45 Detachably arranged within the wash boiler is a draining device comprising a circular flat plate 4 provided with a plurality of circular openings 5 and arranged in these

openings are the upper ends of tubular legs 6 that support the plate 4 in a superimposed position relatively to the bottom plate 50 2. The tubular legs 6 serve as drain pipes and the upper ends of said legs are soldered or otherwise connected to the bottom side of the plate 4, as at 7. The plate 4 has a central opening 8 and mounted in said opening 55 is the lower end of a tubular vertical handle rod 9. The handle rod 9 is retained within the opening 8 of the plate 4 by solder 10 or other fastening means and the upper end of said handle rod extends above the upper 60 edge of the boiler and has a handle 11. The handle rod 9 is perforated, as at 12, said perforations constituting drain openings, and the lower end of the rod terminates at a point above the bottom plate 2, whereby wa- 65 ter can readily drain from the hollow handle rod.

The plate 4 is approximately the same diameter as the shell, adjacent to the bottom plate 2 and it is upon this superimposed 70 plate that clothes can be placed for boiling purposes. After the clothes have been boiled the plate 4 can be elevated through the medium of the handle 11 and water from the clothes can drain through the perforations 12 and the tubular legs 6.

The handle 11 can be made of wood or an insulation material and the remainder of the boiler of light and durable noncorrodible material.

80 What I claim is:

The combination with a wash boiler, of a superimposed plate, tubular legs supporting said plate above the bottom of said wash boiler, and a tubular handle rod connected to 85 said plate and extending above the upper edge of said boiler.

In testimony whereof I affix my signature in the presence of two witnesses.

ALEKSANDER TONKIEWITZ.
